ATTORNEY

UNITED STATES PATENT OFFICE

ALFRED F. POEHL, OF ALGOMA, WISCONSIN

ADJUSTABLE BASE FOR AUTOMOBILE JACKS

Application filed October 30, 1929. Serial No. 403,562.

This invention relates to an adjustable base for automobile jacks, the general object of the invention being to provide a central member which is adapted to be connected to the base of a jack and a pair of side members which are slidably connected with the central member so that said side members can be moved outwardly to increase the length of the base when the jack is used on soft surfaces, such as muddy roads or the like.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a view, partly in section, showing the device in use.

Figure 2 is a bottom plan view of the device.

Figure 3 is a view similar to Figure 1, but showing the side extensions in position under the central member.

Figure 4 is an end view of the device.

In these views, the numeral 1 indicates the central member which is adapted to be connected with the base of the jack A by the screws 2 and the numerals 3 indicate a pair of side members which are slidably connected with the central member by the bolts 4 passing through slots 5 in the side members and through the ends of the central member, each bolt having a wing nut 6 thereon. The central and side members are of channel shape in cross section, as shown.

From the foregoing it will be seen that the device forms a base of considerable area for the jack so that the jack will not sink into mud or other soft surfaces when in use and if the base, with the side members in their inward position, is not sufficient to prevent this sinking of the jack, then the side members can be moved outwardly by loosening the thumb nuts and pulling the side members outwardly until the bolts engage the inner ends

of the slots in the side members, after which the thumb nuts are tightened. This will give a base of considerable length, which will prevent the jack sinking in the soft surface. After the jack has been used, the side members are pushed inwardly again so that the combined jack and base will occupy but little space when placed in a tool box or under the seat.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A base for a jack comprising a central member adapted to be fastened to the base of the jack, a side member at each end of the central member and means for slidably connecting the side members with the central member.

2. A base for a jack comprising a central member adapted to be fastened to the base of the jack and a side member slidably connected with each end of the central member, each side member having a slot therein, a bolt passing through the slot and through the central member and a thumb nut on the bolt.

In testimony whereof I affix my signature.

ALFRED F. POEHL.
